CLAIM

The ornamental design for a camera, as shown and described.

DESCRIPTION

FIG. 1 is a front, left, and top perspective view of a camera embodying the new design;

FIG. 2 a rear, right, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof; and,

FIG. 8 is a top plan view thereof.

The broken lines showing of the camera mount illustrates the environment of the claimed design and forms no part thereof. The remaining broken lines in the drawings illustrate portions of the camera and form no part of the claimed design.

1 Claim, 5 Drawing Sheets
